Assign to

The Lowell Manufacturing Company.

Letters Patent No. 1800-Dated July 16th 1864.

Design for a Carpet Pattern.

The schedule referred to in these Letters Patent and making part of the same.

To all whom it may concern:

Be it known that I, Elmir J. Mey of Lowell, in the County of Middlesex and State of Massachusetts, have originated and designed a new Pattern for Carpets or other fabrics, of which the following is a full, clear and exact description, reference being had to the accompanying drawings, making part of this specification.

This design consists of combinations of gourds, palm leaves, blocks, leaves and other figures of a Persian style, the whole being so arranged as to constitute the particular pattern shown in the drawings.

The colors employed for the different portions of the design, may be varied to suit the taste and wish of the manufacturer.

~ Claim ~

What I claim as my invention, and desire to secure by Letters Patent, is the Design or Pattern for Carpets or other fabrics, here in set forth.
